ATTORNEY.

UNITED STATES PATENT OFFICE.

ROZY KRAUZIEWICZ, OF PITTSBURGH, PENNSYLVANIA.

DESIGN FOR A BODICE.

54,932.

Specification for Design. Patented Apr. 20, 1920.

Application filed August 23, 1919. Serial No. 319,501. Term of patent 3½ years.

To all whom it may concern:

Be it known that I, ROZY KRAUZIEWICZ, a citizen of Poland, and a resident of Pittsburgh, in the county of Allegheny and State of Pennsylvania, have invented a new, original, and ornamental Design for a Bodice, of which the following is a specification, reference being had to the accompanying drawings, forming part thereof.

Fig. 2 is a rear elevational view thereof.

I claim—

The ornamental design for a bodice as shown.

ROZY KRAUZIEWICZ.
